DESIGN FOR A GRIP FOR SANITARY BELTS

Irvin S. De Woskin, University City, Mo., assignor to Beltx Corporation, St. Louis, Mo., a corporation of Missouri

Application January 24, 1946, Serial No. 125,935

Term of patent 14 years

(Cl. D17—9)

To all whom it may concern:

Be it known that I, Irvin S. De Woskin, a citizen of the United States and a resident of University City, in the county of St. Louis and State of Missouri, have invented a new, original, and ornamental Design for a Grip for Sanitary Belt, of which the following is a specification, reference being had to the accompanying drawing, forming part thereof.

Fig. 1 is a front elevational view of a grip for a sanitary belt showing my new design; and Fig. 2 is a side elevational view of the same.

I claim:

The ornamental design for a grip for sanitary belts, as shown.

IRVIN S. DE WOSKIN.
